TEXTILE RUG

Ruth E. Bachrach and Marcella H. Bachrach, both of
4920 30th St. N.W., Washington, D.C. 20008

Filed Sept. 4, 1969, Ser. No. 19,011

Term of patent 14 years

Int. Cl. D6—05

U.S. Cl. D92—21

The figure is a top plan view of a textile rug showing our new design, the rug being flat and of conventional thickness. The light background is for convenience of illustration, only.

We claim:

The ornamental design for a textile rug, substantially as shown and described.
